TYPEWRITER CLEANING DEVICE

André Thorens, Yverdon, Switzerland, assignor to
 Paillard S. A., Sainte-Croix, a corporation of
 Switzerland

Application June 10, 1948, Serial No. 32,099
 In Switzerland May 23, 1947

5 Claims. (Cl. 197—40)

1

Modern typewriters are always fitted with a casing intended to protect their mechanisms. This casing has generally a horizontal part arranged above the type bars. This horizontal part is generally situated approximately at the height of the writing line on the cylinder and has in its middle part an opening for the passage of the type bars when the keys are operated.

In the known typewriters, the casing stops at a certain distance from the cylinder and no separation at all is provided between the cylinder and the space occupied by the type bars and the various mechanisms of the machine. As a consequence, dust and particularly india-rubber waste—when erasures are made—fall directly into the mechanisms and there is a risk of their interfering with their proper working. So the known typewriter casings do not reach the desired aim or reach it only to a certain extent.

The present invention relates to a typewriter including a cylinder fitted on a carriage capable of moving transversally with respect to the machine frame and provided with a casing having a horizontal part protecting the type bars and situated approximately at the height of the writing line on the cylinder, this horizontal part having an opening intended for the passage of the type bars when the keys are operated. This machine has a casing including an inclined wall linked to the horizontal part situated above the type bars and so arranged as to separate the cylinder from the space containing the type bars and extending as far as below the cylinder, this wall leading to a gutter provided approximately in the vertical plane passing through the axis of the cylinder and intended to collect the dust and waste. This machine is in addition fitted with means causing an automatic cleaning of the gutter.

The attached drawing shows diagrammatically and by way of example a form of execution of the typewriter which is the subject of the invention.

Fig. 1 is a perspective view.

Fig. 2 is a simplified lateral view on a smaller scale.

Fig. 3 is a perspective view with portions broken away.

Fig. 4 is a part cross-sectional view.

The typewriter represented by the drawing includes a cylinder 1 fitted on a carriage 2. This carriage is capable of moving transversally with respect to the frame of the machine. For this purpose rails or guides 3 are rigidly fixed to the frame and form runways for balls 4 mounted in

2

housings 5 provided in supports 6 rigidly fixed on the carriage 2.

The machine includes in addition a casing 7 encircling and covering the frame in such a way as to protect the mechanisms from the dust. This casing has an horizontal part 8 situated above the type bars (which are not represented) when said type bars are in their rest position. This part is interrupted at a certain distance from the cylinder and has an opening 9 in its middle part and intended for the passage of the type bars when the keys are operated.

An inclined wall 10 connected to the said horizontal part 8 of the casing is arranged in such a way as to separate the cylinder from the space containing the type bars. This wall 10 leads to a gutter 11 approximately situated in the vertical plane passing through the axis of the cylinder.

The opening 9 exists only on part of the height 20 of the inclined wall 10. In order to allow the free displacement of the type bars, this wall has an embossing 13 situated in front of the opening 9. The most protruding part of this embossing is situated in the middle plane of the typewriter.

Finally, the gutter 11 is divided into two portions which meet in the said middle plane of the machine and are inclined from this plane towards the side walls of the machine. Thus the highest point of the gutter is situated in the middle plane of the machine.

The gutter 11 includes a wall 12 adjacent to one of the rails 3 for guiding the carriage 2. The space situated between the two rails is closed by an L-shaped wall so as to provide a free section sufficient for the passage of the carriage 2.

The rail 3 situated beneath the cylinder lies close to the rear wall 12 of the gutter 11. The L-shaped wall 14 has an opening 16 intended for the passage of a ribbon 17 subjected to the action of a spring (which is not represented) and tending to bring back the carriage towards the left part of the drawing.

From the above description and from examining the attached drawing, one can see that the space delimited by the frame and containing the mechanisms and the type bars is entirely closed and separated from the cylinder, the carriage moving in a trough formed by the inclined wall 10, the gutter 11 and the L-shaped wall 14 linking together the rails 3. Thus the dust and waste (particularly the india-rubber waste formed when erasures are made) can no longer reach the mechanisms and hinder their proper working. The dust and waste falling on the inclined wall 10 slide along said wall and are collected in the

gutter 11. The latter being divided into two portions inclined from the middle plane of the machine towards the lateral sides of said machine, the waste slides under the influence of the typing vibrations and is evacuated.

Finally the mechanisms (transmission parts, escapement, etc.) which are situated under the cylinder and extend towards the rear part of the latter, are entirely separated from the carriage and from the cylinder by the L-shaped wall 14 linking together the two rails 3, of which one lies close to the rear wall 12 of the gutter 11.

In the alternative design shown by Figs. 3 and 4, one finds again the inclined wall 10 of the casing which leads to the gutter 11 approximately situated in the vertical plane passing through the axis of the cylinder 1. The bottom 11 of this gutter is situated in a horizontal plane parallel with the axis of the cylinder 1. This cylinder is carried by a carriage 2 capable of moving with respect to the frame 15 of the typewriter thanks to a guiding device including rails 3 and 8 between which are imprisoned balls 4.

A cleaning device for the gutter 11 is fixed to the carriage. This cleaning device is constituted by a small brush 26 rigidly fastened to an element 6 of the carriage. This brush is preferably situated in the middle transversal plane of the carriage so that during the typing work, it sweeps the gutter 11 over its whole length, but one could also provide two cleaning parts fixed to the carriage and arranged in such a way with respect to each other that the gutter would be cleaned over all its length.

Practical tests carried out with a typewriter fitted with a cleaning device such as described above have shown that it is of advantage to provide the gutter 11 with a perfectly smooth bottom and to arrange things so that the face 18 of the cleaning part shall be situated quite closely to this bottom 11, but shall not be in actual contact with the latter.

Indeed, when the face 18 of the cleaning device touches the bottom 11, some india-rubber waste remains caught and rolls between these two surfaces 18 and 11 during the displacements of the carriage but is never evacuated. On the contrary, when there is a slight distance between these two surfaces, the india-rubber waste is pushed and evacuated, so that the gutter being continually swept by the cleaning device during the typing work, owing to the displacements of the carriage, no accumulation of waste or dust can take place, these being evacuated as soon as they fall into the gutter 11.

Thus india-rubber waste can no longer pass through the slot 17 existing between the wall 12 of the gutter and the rail 3 and cannot become a hindrance to the proper working of the mechanical parts of the typewriter.

Two forms of execution of the typewriter which is the object of the invention have been described herein by way of example and with reference to the attached drawing, but it is obvious that the various elements and parts described can easily be replaced by their equivalents.

Thus the cleaning device here represented under the form of a brush could be replaced by any other cleaning device such, for instance, as a 70 felt.

I claim:

1. In a typewriter including a cylinder car-

ried by a carriage, type bars and a casing protecting the said type bars, the casing having an opening in its middle part and permitting the passage of the type bars on their way to strike the cylinder, an inclined wall fastened to the said casing and extending as far as below the cylinder and separating the latter from the space containing the type bars, a gutter at the lower edge of the said inclined wall and intended to collect dust and india-rubber waste, this gutter being approximately situated in a vertical plane passing through the rotation axis of the cylinder, and means for automatically cleaning the gutter.

2. In a typewriter in accordance with claim 1, in which the means for automatically cleaning the gutter comprises two gutter portions inclined from the middle towards the sides of the typewriter, the bottom of the gutter being flat and smooth so that by the vibrations caused by the operation of the typewriter, said waste and dust are automatically evacuated.

3. In a typewriter in accordance with claim 1 and in which the means for automatically cleaning the gutter comprises a gutter-cleaning device fastened to the carriage of the typewriter.

4. Typewriter in accordance with claim 1, in which the bottom of the said gutter is flat and smooth and parallel with the axis of rotation of the cylinder, the means for automatically cleaning the gutter comprises a gutter-cleaning device fixed to the carriage of the typewriter, and of which the lower surface is situated at a slight distance from the bottom of the gutter, but does not actually touch the bottom of the gutter.

5. In a typewriter including a cylinder carried by a carriage, type bars and a casing protecting the said type bars, this casing having an opening in its middle part and permitting the passage of the type bars on their way to strike the cylinder, an inclined wall fastened to the said casing and extending as far as below the cylinder and separating the latter from the space containing the type bars, a gutter fastened to the lower edge of the said inclined wall and intended to collect dust and india-rubber waste, this gutter being approximately situated in a vertical plane passing through the rotation axis of the cylinder, rails on which the carriage moves, an L-shaped wall interconnecting the said rails, the whole so arranged as to separate the cylinder from the space containing the typewriter mechanisms protected by the said casing and which extends towards the rear part of the typewriter as far as below the said cylinder, and means for cleaning the gutter provoking an automatic cleaning of the latter during the operation of the typewriter.
